L. A. HOERR

CAR DOOR

Filed Sept. 23, 1922

INVENTOR
L. A. HOERR

BY *E. E. Kappman*
ATTORNEY

UNITED STATES PATENT OFFICE.

LOUIS A. HOERR, OF ST. LOUIS, MISSOURI.

CAR DOOR.

Application filed September 23, 1922. Serial No. 590,048.

To all whom it may concern:

Be it known that I, LOUIS A. HOERR, a citizen of the United States of America, residing at the city of St. Louis, State of Missouri, United States of America, have invented certain new and useful Car Doors, of which the following is such a full, clear, and exact description as will enable any one skilled in the art to which it appertains to make and use the same, reference being had to the accompanying drawings, forming part of this specification.

Heretofore it has been customary to provide car doors with a strengthening strip in the form of an angle iron or Z-bar, one web or flange of the strip abutting directly against the lower edge of the door. I have found that water is conducted between the lower edge of the door and strengthening strip by the grooves in the face of the door siding. As no effective provision is made for draining off this water, nor any provision whatever for ventilating the lower edge of the door, the result is that this part of the door remains almost constantly moist with the result that in a comparatively short time the wood becomes decayed so that the fastening bolts are easily torn out and the strengthening strip carried away.

The object of my invention is to so construct the car door as not only to drain off the water from the lower edge thereof, but also to provide effective ventilating means for the same so as to overcome the objection above referred to.

In the accompanying drawings which illustrate the form of door structure made in accordance with my invention, together with a modification thereof, Figure 1 is a vertical section, Figure 2 is a section taken on the line 2—2 of Figure 1, Figure 3 is a section taken on the line 3—3 of Figure 1 and Figure 4 is a view similar to Figure 1 but having a modification.

5 indicates a portion of the side of a car and 6 the door battens. Secured to the battens 6 are siding strips 7 vertically disposed and tongued and grooved together. These strips 7 have their edges chamfered in the usual manner so as to form vertical channels 8 in the face of the door producing run-ways for rain or melted snow. In addition to these channels 8, when wide siding strips are used, the strip has a similar central channel 9 formed in it.

In carrying out the preferred form of my

invention, I secure to the lower edge of the door a Z-bar 10 and a flat bar 11. These bars are held in place by bolts 12 passing through the door. I also prefer to secure the two bars together by rivets 13. In order to secure a suitable ventilating space between the lower edge of the door and the Z-bar, I provide the said bar with suitable spacing stops. These spacing stops may be formed by punching up portions 14 of the central web of the Z-bar as shown in the drawings. This construction not only secures an adequate ventilating cell 15 but also provides openings 16 for draining off the water and admitting air to the ventilating cell 15. A guide bracket 17, secured to the car 5 by bolts 18, cooperates with the lower flange of the Z-bar to prevent the door from swinging outwardly.

In Figure 4 I have shown a modification in which the Z-bar 10 and flat bar 11 are replaced by a single U-shaped bar 19. This U-bar has spacing stops 14 struck up from its central part in the same manner as the Z-bar hereinbefore described. In this construction, the bracket 17 is replaced by a bracket 17' adapted to cooperate with the front flange of the U-bar 19 to prevent the outward swing of the door.

By my construction, the water is effectively drained from the lower edge of the door so as to prevent soaking the same where the end of the grain is exposed and at the same time adequate ventilation is secured to rapidly dry out the moisture which is necessarily imparted to it in spite of the drainage.

Having fully described my invention what I claim as new and desire to secure by Letters Patent of the United States is:

1. In a device of the class described, the combination with a wooden door, of a reinforcing strip provided with a vertical and a horizontal web, the horizontal web being positioned away from the lower edge of the door to form a ventilating space to dry the wood.

2. In a device of the class described, the combination with a wooden door, of a reinforcing strip provided with a vertical and a horizontal web, fastening means for said strip, and a stop independent of the fastening means to position the horizontal web away from the lower edge of the door to form a ventilating space to dry the wood.

3. In a device of the class described, the combination with a wooden door, of a rein-

forcing strip provided with a vertical and a horizontal web fastening means for said strip, and an integral stop independent of the fastening means to position the horizontal web away from the lower edge of the door to form a ventilating space to dry the wood.

4. In a device of the class described, the combination with a door, of a reinforcing strip provided with a vertical and a horizontal web and carrying a stop to position its horizontal web away from the lower edge of the door to form a ventilating space, said stop being cut out of the strip to form a draining and ventilating opening.

5. In a device of the class described, the combination with a door provided with chan-

nels in its vertical face, of a reinforcing strip provided with a vertical and horizontal web, the horizontal web being positioned away from the lower edge of the door to form a drainage space communicating with the channels in the face of the door.

6. In a device of the class described, the combination with a wooden door comprising vertical strips, of a reinforcing metallic strip positioned away from the lower end of the door to form a ventilating cell for the exposed end grain of said vertical wooden strips.

In testimony whereof, I have hereunto set my hand and affixed my seal.

LOUIS A. HOERR. [L.S.]
